UNITED STATES PATENT OFFICE

92,707

DESIGN FOR A SPACE HEATER OR ARTICLE OF ANALOGOUS NATURE

Edwin Esson, Newton, Mass., assignor, by mesne assignments, to Johnson Products Co., Boston, Mass., a corporation of Massachusetts

Application May 1, 1934, Serial No. 51,602

Term of patent 7 years

To all whom it may concern:

Be it known that I, EDWIN ESSON, a subject of the King of Great Britain, residing at Newton, in the county of Middlesex and Commonwealth of Massachusetts, have invented a new, original, and ornamental Design for a Space Heater or Article of Analogous Nature, of which the following is a specification, reference being had to the accompanying drawing forming a part thereof.

The figure is a view in perspective of the article showing my new design.

I claim:

The ornamental design for a space heater or article of analogous nature, substantially as shown.

EDWIN ESSON.
